STOVEPIPE COLLAR AND ANCHOR

Albertus Upton, Waveland, Ind.

Application May 5, 1936, Serial No. 78,014

3 Claims. (Cl. 126—318)

This invention relates to fastening means for stovepipes.

The main object is to provide means whereby a stovepipe will be securely held in an opening in a chimney wall.

Another advantage of the invention resides in the simplicity of construction, and the cheapness of manufacture.

Other objects and advantages of the invention will become apparent from the drawing and the following description.

In the drawing:—

Figure 1 is a side elevation of the device as applied to a stovepipe, the stovepipe being shown as applied to a flue opening in a chimney wall, the wall being shown in section;

Figure 2 is a side elevation of the rings and connecting means;

Figure 3 is an elevational view of one end of the device;

Figure 4 is a similar view of the opposite end thereof;

Figure 5 is a sectional detail on the line 5—5 of Figure 4;

Figure 6 is an enlarged fragmentary view showing the connecting means for the ends of the larger ring as shown in Figure 3, and

Figure 7 is a modified form of said connecting means.

Referring more particularly to the drawing wherein like reference characters designate corresponding parts in the different views, 10 is a chimney wall, having a flue opening 11 therein. A stovepipe 12 has an elbow 13. A collar 14, of the ordinary type, is mounted on the stovepipe 12 and bears against the outer face of the wall 10.

The fastening means comprises two rings 15 and 16 and metal straps 17 to connect the rings. The ring 15 has offset loop portions 18 extending

inwardly toward the axis of the ring as best shown in Figure 3. The ring 16 has loops 19 offset inwardly as shown at 19' and extended rearwardly as best shown in Figure 2 at 19''. The straps 17 are secured to the offset portions 18 by

rivets 20 or by any other suitable means. The free ends of the straps 17 are bent around the offset portions 19 as best shown in Figure 5 after the parts are assembled as shown in Figure 1.

The larger ring 15 has one of its ends formed in a loop 21. The other end of the ring is offset as at 22 to allow the end to enter the loop 21, said offset portion cooperating with the loop to form a stop as best shown in Figure 6.

A strand of wire 23, as shown in Figure 1, has one end secured to the ring 16 the other end extending around the elbow 13 and tied at 24 to assist in holding the pipe 12 in the opening 11.

In Figure 7 is shown a modified means for connecting the loose ends of the ring 15. In this form each of the ring ends is returned as shown at 25 and 26, respectively, and their extremities formed into U-shapes 27 and 28, respectively, that interengage, as shown, when the ring is completed. One of said returned portions is preferably offset as shown at 29.

In installing the device the ends 21 and 22 of ring 15 are disconnected and the ring 15 is then contracted and passed through the flue opening 11 after which the ends are again connected.

The straps 17 secured to the portions 18 extend through the opening. The pipe 12 carrying the collar 14 and ring 16 is then inserted in the opening 11, with the straps 17 on the outside of the pipe 12. The straps 17 are then bent about the portions 19 of ring 16 this causing the ring 15 to abut against the inner face of the chimney wall 10. The ring 16 bears against collar 14 and the tension of straps 17 tends to draw portions 19 inwardly thereby causing straps 17 to frictionally engage pipe 12. The wire strand 23 is then secured at one end to ring 16 and the opposite end is tied around elbow 13 to more securely hold the pipe 12 in flue opening 11.

It is to be understood that only the preferred embodiment of the invention is herein shown and described. Various changes and modifications can be made without departing from the spirit and scope of the invention.

I claim as my invention:—

1. Fastening means for a stovepipe, comprising two wire rings having offset portions, metal bands secured to said offset portions and connecting the rings, one of said rings being adapted to engage in a chimney opening, the other ring being carried by a stovepipe and engaging the outer face of the chimney.

2. A device as in claim 1, one of said rings being an open ring and having one of its ends formed with a loop, and its other end offset to engage in said loop and to provide a stop to limit the closure of the ring.

3. A stovepipe fastener, comprising in combination, two resilient wire rings adapted to be positioned one on each side of a flue opening, corresponding offset portions in said rings adapted to be engaged by metal straps to connect said rings, and a strand of wire secured at one end to an elbow of a pipe, the opposite end of said strand engaging the nearest ring to hold the pipe in position in the flue.
